SLIDER FOR A SLIDING CLASP FASTENER

Joachim Backer, Whitchurch, Cardiff, and Henry D. Koppel, Rhwbina, Cardiff, Wales, assignors to Aero Zipp Fasteners Limited, London, England, a company of Great Britain

Application November 15, 1955, Serial No. 547,006

Claims priority, application Great Britain
September 5, 1955

6 Claims. (Cl. 24—205.15)

The present invention relates to a slider for a sliding clasp fastener of the kind comprising opposed shields for guiding two fastener stringers of the sliding clasp fastener through the slider, the said shields being so arranged as to allow spreading apart of the two shields to enable at least one of the stringers to be removed from the slider, for example for overcoming jamming when the slider may have jammed on the stringers.

It is an object of the invention to provide such a slider, which is easy to manufacture and operate.

It is another object of the invention to provide such a slider which in normal use is securely locked against unintentional spreading, but which can easily be spread when desired.

It is a further object of the invention to provide such a slider which can be spread by simply pressing a pull member as ordinarily provided against the slider body.

It is still another object to provide such a slider, where-in the locking and spreading mechanism is concealed to a great extent.

These and other objects and advantages of the invention will become apparent to those skilled in the art from the following detailed description of an embodiment of the invention when read with reference to the accompanying drawings, which are given by way of example and in which:

Fig. 1 is a perspective view of a portion of a sliding clasp fastener comprising a slider of the invention;

Fig. 2 is a view similar to Fig. 1, but showing the slider shields spread apart, and one of the fastener stringers retained by the slider while the other stringer is removed from the slider;

Fig. 3 is an exploded perspective view of the slider;

Fig. 4 is a side view of the assembled slider, partly in section, and to a larger scale than Figs. 1 to 3, showing the slider in its closed position;

Fig. 5 is a side view similar to that of Fig. 4, and to the same scale, but with the slider shields spread apart;

Fig. 6 is a sectional inverted view along the line VI—VI of Fig. 4; and

Fig. 7 is a sectional view along the line VII—VII of Fig. 4.

The sliding clasp fastener shown in Figs. 1 and 2 comprises two stringers generally indicated by reference numerals 22 and 28. The stringers 22 and 28 respectively comprise carrier tapes 29 and 30, provided with interlocking members 21. The fastener is opened and closed in known manner by a slider generally indicated by reference numeral 31.

The slider 31 (see also Figs. 3 to 7) comprises two opposed slider shields 1 and 2, a pull member 17 for operating the slider, and a spring 11.

The slider shield 1 having a narrow end and a wide end comprises side walls 3 and 33 on its base and a riser element 5 having a wedge-shaped portion 6 directed towards the narrow end of the shield 1, a portion 9 overhanging the base of the shield 1, a tail portion 10, a platform 35, and a retaining plate 7.

2

The riser element 5 has a pivot hole 8 and a bore 24 at right-angles thereto, both parallel to the base of the shield 1, and the bore 24 extending in the longitudinal direction of the shield 1. The bore 24 is blind at one end adjacent the wedge-shaped portion 6 and open at its other end adjacent the tail portion 10 of the riser element 5. The side walls 3 and 33 of the shield 1 extend from the narrow end of the shield to about half way along the shield. The riser element 5 is unitary with the base and extends generally in the longitudinal direction of the base from the wide end of the shield 1, towards about the centre thereof. The retaining plate 7 is parallel to the base and spaced therefrom substantially by the width of the interlocking members 21 (that is to say, the dimension of the said members perpendicular to the plane of the tapes 29, 30), the retaining plate 7 extending laterally from and beyond the wedge-shaped portion 6 of the riser element 5.

The slider shield 2 has a narrow end and a wide end, and is provided with a longitudinal substantially central aperture 12 bordered towards the narrow end by an edge 23. An additional aperture 16 is formed by an extension of one corner of aperture 12 towards one side and towards the narrow end of the shield 2. At its wide end, the shield 2 is provided, adjacent the aperture 12, with a spring abutment face 13, with a surface 14 inclined to the general plane of the shield 2 and directed away from the adjacent end of the slider shield 2, the surface 14 being joined to the spring abutment surface 13 by a surface 114, with a fulcrum portion 25, and with a bevelled face 26 joined to the surface 14 by a surface 15. The side of the shield 2 which faces the shield 1 has a recess 27 for receiving the retaining plate 7. Side walls 4 and 34 of the shield 2 extend from the narrow end of the shield 2 to about half way along the shield.

The pull member 17 has pivot pins 19, an abutment portion 18, and a locking projection 20.

The spring 11 is a helical compression spring.

For assembling the slider, the spring 11 is introduced into the bore 24 so that the greater part of the spring 11 is housed in the said bore 24. The shield 2 is placed over the riser element 5 of the shield 1 so that the spring 11 contacts the spring abutment face 13 of the shield 2. The spring 11 is now compressed by moving the shield 2 relatively to the shield 1 until the edge 23 of the shield 2 passes the overhanging portion 9 of the riser element 5. The shield 2 is then released and the spring 11 displaces the shield 2 relatively to the shield 1 until the edge 23 lies below the overhanging portion 9. The pivot pins 19 of the pull member 17 are engaged in the pivot hole 8 of the riser element 5 and the arms of the pull member which bear the pivot pins 19 are compressed together so as to be eventually parallel. Thereby the pull member 17 is secured to the riser element 5. The action of the spring 11 on the spring abutment face 13 of the shield 2 causes the shield 2 to be held, with its edge 23, which borders the aperture 12, engaged with an adjacent surface of the overhanging portion 9 of the riser element 5 and the shield 1, the retaining plate 7 of the riser element 5 being engaged in the recess 27, and the fulcrum portion 25 of the shield 2 resting on platform 35, while the surface 115 lies close to an adjacent surface of the tail end 10 of the riser element 5. The assembled slider in its normal operating position is shown in Figs. 1 and 4.

The shield 2 is displaceable relatively to the other shield 1 and the riser element 5 against the action of the spring 11, this displacement being possible without the shield 2 being moved out of its position of parallel relationship with the shield 1. On reaching, during such displacement, a position in which the overhanging portion 9 of the riser element 5 lies over the aperture 12, the edge 23 of the shield 2, which borders the aperture

12, just clearing the overhanging portion 9 of the riser element 5, the shield 2 is no longer constrained to remain parallel to the shield 1, and can be spread apart from the shield 1 by turning the shield 2 relatively to the shield 1 about the fulcrum portion 25, which although displaced in the longitudinal direction of the slider, continues to rest on the platform 35. When the slider is in its operative position shown in Figs. 1 and 4 and it is intended to spread the shields 1 and 2 apart, for example when the slider has jammed on the stringers, due, for instance, to the presence of foreign matter in the slider, the pull member 17 is turned in an anti-clockwise direction (when viewed as shown in Fig. 4) relatively to the riser element 5 until the abutment portion 18 of the pull member 17 contacts the inclined surface 14 of the shield 2. Further turning of the pull member 17 in the same direction causes the abutment portion 18 to press with a camming action against the inclined surface 14 of the shield 2, thereby causing the shield 2, which is constrained by the overhanging portion 9 of the riser element 5 to remain parallel to the shield 1, to be displaced in its longitudinal direction relatively to the riser element 5 until the edge 23 of the shield 2, which borders the aperture 12, has cleared the overhanging portion 9 of the riser element 5, so that the shield 2 is no longer constrained by the overhanging portion 9 of the riser element 5 in its position parallel to the shield 1. Still further turning of the pull member 17 causes pressure to be applied by the pull member 17 to the inclined surface 14 of the shield 2. Since the shield 2 is no longer constrained by the overhanging portion 9 of the riser element 5 the shield 2 is caused to pivot about the fulcrum portion 25, which rests on the platform 35, so that the narrow end of the shield 2 recedes from the narrow end of the shield 1, the spreading being permitted by a clearance between the bevelled face 26 of the shield 2 and the platform 35 of the riser element 5. The amount of spreading is limited by the outer face of the shield 2 abutting against the pull member 17. The position of the slider when its shields 1 and 2 are fully spread is shown in Figs. 2 and 5.

When it is subsequently intended to close the slider, it is only necessary to press the narrow ends of the shields 1 and 2 together into their parallel positions, whereupon the shield 2 is automatically displaced longitudinally into its original position with a snap action due to the action of the spring 11 so that the overhanging portion 9 of the riser element 5 re-engages the edge 23 and, again, constrains the shield 2 to remain parallel with the shield 1.

When the pull member 17 is in the position shown in Fig. 1, the locking projection 20 enters the additional aperture 16 and engages between adjacent interlocking members 21, whereby the slider is locked in position on the stringers 22 and 28. To release the slider for closing and opening the fastener, the pull member 17 is turned anti-clockwise out of its position shown in Fig. 1, whereby the locking projection 20 is lifted out of engagement between adjacent interlocking members 21.

When the shields 1 and 2 are in the position shown in Fig. 5, the retaining plate 7 prevents the stringer 22 (see Figs. 1 and 2) from being removed from the slider. This prevention is achieved by arranging the retaining plate 7 so that it extends towards the narrow end of the shield 1 past the diverging end of the side wall 33 of the slider shield 1. In this way, the stringer 22 can slidably move in the channel formed by the shield 1, side wall 33, and the retaining plate 7, but cannot be separated from the slider.

Modifications of the embodiment described are possible. For example, the pull member may be dispensed with, in which case, opening is effected by displacing the shield 1 manually. Again, the arrangement may be such that on spreading the slider, the abutment portion 18

of the pull member abuts against the surface 15 of the slider shield 2 instead of against the surface 14.

It should be clearly understood that the embodiment described is given by way of example only. Various modifications, additions and omissions are possible without departing from the spirit of the invention.

We claim:

1. A slider for a sliding clasp fastener, comprising two opposed slider shields for guiding two fastener 10 stringers through the slider, a riser element provided in fixed position on one of said slider shields and extending through an aperture in the other slider shield, a support on said riser element, the said support carrying said other slider shield displaceably in substantially parallel 15 relationship to said one slider shield, a portion on said riser element, the said portion normally overhanging an edge of said other slider shield bordering the said aperture, an abutment on said other slider shield, spring means acting between the said abutment and the said 20 riser element, the said spring means urging the said edge into a position underneath the said overhanging portion, and fulcrum means on the said other shield, the said other shield together with its fulcrum means being displaceable along the said support without substantial change of its general plane against the action of the said spring means to such an extent that the said edge clears the said overhanging portion of the riser element, the arrangement being such the spreading of the 25 slider shields relatively to each other is effected by first displacing the said other shield along said support to clear the said overhanging portion so that the said other shield is no longer constrained to remain in the same general plane, and subsequently turning the said other shield relatively to the said one shield about the said 30 fulcrum means.

2. A slider as claimed in claim 1, and comprising a pull member turnably mounted to said riser element and having an abutment surface arranged for co-operation with a surface of said abutment of said other shield, the arrangement being such that, on pressing the said surfaces together by turning the pull member, a camming effect is obtained between the said pull member and the said abutment, whereby the said other shield is first displaced to clear the said overhanging portion and is subsequently, on further pressing, turned relatively to the said one shield.

3. A slider as claimed in claim 2, wherein the said surface of the said abutment is inclined to the general 40 plane of the said other shield.

4. A slider as claimed in claim 1, wherein the said fulcrum means comprise a fulcrum abutment bearing against and slidably on the said support.

5. A slider as claimed in claim 1, wherein the spring 55 means are in the form of a compression spring at least the greater part of which is contained within a bore in the riser element the said bore having an open end remote from the said overhanging portion of the riser element, and a closed end nearer to the said overhanging portion.

6. A slider as claimed in claim 5, and comprising a retaining plate provided on the support substantially parallel to the said one shield and arranged at one side only of the said riser element, the said other shield having a recess for normally accommodating the said retaining plate, which disengages the said recess when the slider is spread, and which serves to retain one of the two stringers of the sliding clasp fastener in the slider when spread.
